Primary Examiner — Cynthia Ramirez*Assistant Examiner* — Gino Colan(74) *Attorney, Agent, or Firm* — Lowe Hauptman & Ham, LLP**CLAIM**

The ornamental design for an electric fluid pressure actuator, as shown and described.

DESCRIPTION

FIG. 1 is a front view of the electric fluid pressure actuator. FIG. 2 is a left side view of the electric fluid pressure actuator. FIG. 3 is a right side view of the electric fluid pressure actuator.

FIG. 4 is a rear view of the electric fluid pressure actuator. FIG. 5 is a top plan view of the electric fluid pressure actuator. FIG. 6 is a bottom plan view of the electric fluid pressure actuator.

FIG. 7 is a right-top perspective view of the electric fluid pressure actuator.

FIG. 8 is a left-top perspective view of the electric fluid pressure actuator.

FIG. 9 is a right-bottom perspective view of the electric fluid pressure actuator; and,

FIG. 10 is a left-bottom perspective view of the electric fluid pressure actuator.

The broken line shown in the figures are included for the purpose of illustrating elements of the electric fluid pressure actuator and form no part of the claimed design.
